UNITED STATES PATENT OFFICE.

THOMAS H. IRELAND, OF ROCKVILLE CENTER, NEW YORK.

HUMIDIFYING SYSTEM.

Application filed April 26, 1924. Serial No. 709,318.

To all whom it may concern:

Be it known that I, THOMAS H. IRELAND, a citizen of the United States, residing at Rockville Center, in the county of Nassau 5 and State of New York, have invented certain new and useful Improvements in a Humidifying System, of which the following is a specification.

This invention pertains generally to humidifying systems and while the principles thereof may be employed for various purposes, the invention is illustrated herein as embodied in a system suitable for household use.

10 One of the primary purposes of this invention is to provide an apparatus which can be readily installed and used in connection with the ordinary house heating system. Furthermore, my invention is designed so 20 that it may be sold as a unit and supplied to heating systems already installed.

Another object of my invention is to provide a system which will be entirely automatic in its operation both as to its water 25 supply and also as to its operation, my invention being designed to operate when the heating system is in operation and to remain idle when the heating system is not in operation. This feature is obviously desirable 30 since a humidifying system is necessary only at such times as the heating system is being used. Another purpose of my invention is to provide an apparatus which will be simple in construction, economical to manufacture, 35 one which can be readily installed by unskilled labor and which will be efficient and reliable in operation.

Other objects and advantages of my invention should be readily appreciated as the 40 same becomes better understood, by reference to the following description when considered in connection with the accompanying drawings.

Referring to the drawings, —

45 Fig. 1 is a plan view of the water tank and apparatus connected therewith embodied in my invention.

Fig. 2 is a side elevation thereof.

Fig. 3 is an end elevation looking at the 50 left hand end of Fig. 2.

Fig. 4 is an elevation of the opposite end of the tank.

Fig. 5 is a fragmentary plan view showing 55 the relation of the moist air delivery pipe to a radiator.

Fig. 6 is a side elevation of my improved apparatus installed in connection with a steam heating system, and

Fig. 7 illustrates the application of my invention to a hot air heating system.

Referring to the drawings more in detail and particularly at first to Figs. 5 and 6, reference character 8 indicates generally a water tank to which water is automatically supplied to maintain a predetermined water level therein as will be later described, the tank being shaped to seat upon and be carried by a steam heating pipe 9 extending from the boiler (not shown) to a radiator 11 resting upon the floor 12 of the room to be humidified. An air intake pipe 13 extending through the floor 12 communicates with the interior of the room at or near the floor and the moist air delivery pipe 14 connected with the opposite end of the tank 8 extends upwardly through the floor a considerable distance in close proximity to the radiator 11 so as to be heated thereby. The water in the tank is heated by the steam pipe 9 and the heat from the radiator causes an upflow of air in the pipe 14 while at the same time the colder air along the floor flows through the pipe 13 to the tank in which it evaporates some of the water from the tank and then passes through the pipe 14 into the room to be humidified. A continuous circulation of air through the humidifying tank is, therefore, maintained whenever the radiator 11 is in operation.

Referring now more particularly to Figs. 1 to 4 inclusive, it will be observed that the tank 8 is elongated in shape and formed to provide a downwardly opening U-shaped channel or recess 15 adapted to fit over the steam pipe 9. The tank when set upon this pipe straddles the same and it is secured in position thereon by a slide 16 which is removed during the positioning of the tank and is then slid into the position shown in Figs. 3 and 4 beneath the guide flanges 17 and 18, thereby fastening the tank to the pipe, and forms a heat retaining chamber.

A water supply pipe 19 communicates with one side of the tank and is provided at a desired level with an over-flow pipe 21 which prevents the water in the tank from rising above a predetermined maximum level. The top of the pipe 19 is preferably equipped with a funnel 22 and water is automatically delivered to the funnel from a

valve 23 located in the water supply pipe 24 preferably connected with a water service pipe. This valve 23 is automatically opened and closed by a pair of floats 25 located in the tank and connected with a rock shaft 26 mounted in suitable bearings 27 at the sides of the tank, the rock shaft being connected through a lever 30 and arm 28 with the valve 23. Through the instrumentality of this float controlled valve the water level in the tank is automatically maintained at a predetermined height.

The air supply pipe 13 to the tank is connected with a nipple 29 at one end of the tank and the entering air is deflected downwardly against the surface of the water in the tank by a hood or deflector 31. An outlet nipple 32 at the opposite end of the tank, preferably larger in diameter than the inlet nipple, is connected with the moist air delivery pipe 14.

Since the circulation of air through the humidifying tank is caused by the heating of the moist air delivery pipe 14 from the radiator, it will be manifest that this circulation will be mainly maintained when the radiator is in operation and but slight, if any, circulation at other times. The evaporation of the water in the tank is facilitated by the heating of the water from the steam pipe 9 and if the heat be sufficient the water may be heated so as to deliver an appreciable volume of moist air through the pipe 14. The water level in the tank is automatically maintained by the float controlled valve so that the apparatus requires no attention over prolonged periods of use.

A modification of the invention is shown in Fig. 7 wherein reference character 33 indicates a hot air furnace from which a hot air pipe 34 leads to the register 35 opening into the room. The water tank 36 in this instance is clamped or otherwise secured in intimate contact with the pipe 34 so as to be heated thereby and it may be substantially of inverted U or other adaptable shape so as to fit over the pipe similarly to the tank previously described. Water is supplied to the tank in the manner previously explained and air is delivered to the tank through a pipe 37 connected with the lower portion of the room as previously described. The moist air delivery pipe 38, however, is preferably connected with the pipe 34 so that air will be forced through the pipe 38 by the lower temperature of the entering air and cause an action which will cause the discharge of the moist air into the pipe 34 from which it will be discharged into the room together with the heated air flowing directly from the furnace.

I have shown and described my invention as applied in a heating system including a radiator or a register, but it should be understood that the invention is of broader

scope, for any heat distributing system may be utilized. In some of the claims, therefore, I have generically referred to all such devices and arrangements as heat distributors.

While I have shown and described preferred embodiments of my invention, obviously the structural details may be varied within considerable limits without departing from the essence of my invention, as defined in the following claims.

I claim:

1. In a heating system, in combination with a room having a pipe for supplying heated medium thereto, a water tank constructed and arranged to be heated by said pipe, means for delivering air from the lower part of said room to said tank, and a moist air delivery pipe leading from said tank so that circulation of air through said tank from said means to said pipe will be positively initiated upon rise in temperature of the water in said tank, and auxiliary means for increasing the rate of circulation of air through said tank.

2. In a humidifying system, in combination with a heat distributor in a room to be heated thereby and a heating medium supply pipe thereto, a water tank connected with said pipe whereby the water in the tank may be heated out of contact with said heating medium, an air inlet pipe leading into said tank, and an air outlet pipe leading from said tank terminating adjacent said heat distributor within said room.

3. In a humidifying system, a heating system including a heat distributor in the room to be humidified, a pipe for supplying a heated medium thereto, a water tank connected to said pipe whereby water in the tank will be heated by the heated medium in said pipe and means for establishing air circulation to and from the water tank from and to the room to be humidified including means disposed in close relation to the heat distributor in the said room.

4. A humidifying system comprising, a heat distributor in the room to be humidified, a pipe for supplying a heated medium to the heat distributor, a water receptacle disposed in heat receiving relation to said pipe, an air pipe extending into said water receptacle above the normal water level therein and from a portion of said room where there is a lower temperature than the temperature of said heat distributor when heated, and a moist air delivery pipe from said receptacle to a point in close proximity to said heat distributor whereby a circulation of air may be maintained through said receptacle.

5. In a humidifying system, the combination with a heating system including a radiator in the room to be humidified, and a heated medium supply pipe thereto, of a water tank connected to said supply pipe

to be heated thereby, an air intake pipe establishing communication between the tank and the lower portion of said room, and a moist air delivery pipe extending from said tank into close proximity to said radiator to be heated thereby.

6. In a humidifying system, the combination of a radiator in a room to be humidified and a supply pipe of a heating system connected to said radiator, a water tank mounted on said supply pipe, means for automatically maintaining a predetermined water level in said tank, an air pipe leading from the lower portion of said room to one end of said tank, a deflector for deflecting the air entering said tank downwardly against the surface of the water therein, and a moist air delivery pipe extending from the opposite end of said tank upwardly into close proximity to said radiator to be heated thereby.

7. In a humidifying system, the combination with a radiator and a supply pipe therefore, of a tank substantially of inverted U-shape supported upon the said pipe, a detachable slide whereby said tank may be secured to the pipe and form a heat retaining chamber thereabout, means for maintaining a predetermined water level in said tank, a pipe connecting one end of said tank with a room near the floor thereof, and a pipe extending from the other end of the tank

upwardly into close proximity to the radiator whereby said pipe may be heated to maintain an air circulation through said tank.

8. In a humidifying system, a heating system including a radiator in the room to be humidified, a pipe for supplying a heated medium to said radiator, a water tank connected to said pipe whereby water in the tank will be heated by the heated medium in said pipe and means for establishing air circulation to and from the water tank from and to said room to be humidified including means disposed in close relation to a portion of the heating system in said room and including means for deflecting air entering said tank into intimate contact with the surface of the water therein.

9. In a humidifying system, a heating system including a radiator, said radiator being disposed in a room to be humidified, a pipe for supplying a heated medium to said radiator, a water tank connected to said pipe whereby water in the tank will be heated by the heated medium in said pipe, means for maintaining a predetermined water level in said tank, and means for establishing air circulation to and from the water tank from and to said room including means disposed in close relation to a portion of the heating system in said room.

THOMAS H. IRELAND.
